ELLIPSOGRAPH INSTRUMENT

Arthur M. Johnson, Greensboro, N.C.

Application March 18, 1957, Serial No. 646,808

8 Claims. (Cl. 33—30)

The present invention relates to an ellipsograph instrument and relates more particularly to an improvement in an ellipsograph instrument in which a novel broad range calibrated beam supporting a drafting instrument carrying carriage is rotatably supported on a guiding framework.

The ellipsograph instrument of this invention is designed to be capable of describing ellipses having virtually an infinite number of ratio combinations, within the limitations of the instrument, for the major and minor axes, and wherein the instrument is capable of describing very small ellipses as well as large ellipses.

Another object of this invention is to provide an ellipsograph which does not require numerous reference positions or lines for guiding the ellipsograph.

It is also an object of this invention to provide an ellipsograph which supports a rotatable calibrated beam having a pivot point on which the beam is rotatable and a drafting instrument supporting carriage rotatably mounted and slidably for various size ellipses on the calibrated beam.

Yet another object of this invention is the provision of an ellipsograph in which a portable framework stand rotatably supports a calibrated beam that is centered at the intersection of the major and minor axes of an ellipse and the calibrated beam supports a slideable and rotatable carriage on which carriage a drawing member is mounted.

Still another object of this invention is to provide an ellipsograph having a calibrated beam in which an offset centering leg that is rotatable with a calibrated beam affords a broader range of ellipses to be drawn.

A further object of this invention is to provide an ellipsograph instrument that is simple to operate, one that is sturdy in construction and may be readily adapted for either a pencil, pen or scribing device.

Other and further objects and many of the attendant advantages of this invention will become more readily apparent as the invention becomes better understood from the following detailed description taken in conjunction with the following drawing in which like characters or reference designate corresponding parts throughout the several views, and wherein:

Fig. 1 is a perspective view of an ellipsograph instrument supported in an operating position and embodying the inventive concept illustrated in one position during the generation of an ellipse;

Fig. 2 is a rear elevational view of the instrument illustrated in Fig. 1 folded in an initial position; and

Fig. 3 is an enlarged partial longitudinal sectional view of a writing member of the ellipsograph disclosed within the circle in Fig. 2.

Referring to the drawing, there is illustrated in Fig. 1 an ellipsograph instrument 10 shown in one operating position upon partially executing an ellipse 11 with the components of the ellipsograph comprising a supporting framework 12 on which a calibrated beam 13 is rotatably supported with the beam 13 having a ground-engaging leg member and pivot point 14 and a drawing

2

instrument supporting carriage 15 that is rotatably and slidably supported from the beam 13 with actuating means supported on the calibrated beam for rotation and displacement of the carriage 15 upon rotation of the beam during generation of an ellipse as will be described hereinafter.

The framework 12 is an open stand having a horizontal member 18 that is provided with a hand grip 19 and a depending ground-engaging leg member 20 that extends 10 downwardly from the member 18 at the end of which leg member is a foot 21 having a notch 22 therein for coincidental alignment on the projected X—X axis which represents the major axis of an ellipse. The other end of the member 18 has secured thereon a depending 15 step shaft 23 at the end of which is a first bevel gear 24 that is fixed on the shaft.

Calibrated beam 13 extends horizontally and is rotatably mounted below the horizontal member 18 on the shaft 23 through an opening in the angle plate 20 bracket 25 that extends normal to the beam. Bracket 25 is formed on the beam intermediate the beam length. The calibrated main portion 26 of beam 13 consists of two sections on which are inscribed a lower scale 27 having thereon inscribed indicia representing the length 25 of the major axis of an ellipse, and an upper scale 29 having indicia inscribed thereon corresponding to various angular projections of an ellipse with an elongated guide slot 28 positioned intermediate the scales 27 and 29. The setting on the scale 27 indicates the full length 30 of the major axis of an ellipse. At one end of the beam there is a free end 30 that a right angle end 31 with a shaft supporting section 33 at a right angle to the calibrated portion of the beam and a terminal finger grasp portion 34 is mounted on the section 33. The other 35 end of the beam 13 has a horizontal section 35 in which there is a return offset 36 in order to make the beam coincide with the plane that includes the axis of the shaft 23. The horizontal portion 35, the vertical reach 36, and the elongated horizontal reach 37 from which the downwardly extending ground-engaging leg 39 projects forms an opening 38 between the horizontal reaches 35 and 37 which opening is for a purpose to be described hereinafter. The ground-engaging leg 39 has a tapered pivot point 40 that is in axial alignment with the axis of shaft 23. It has been found desirable to extend the point 40 slightly to compensate for some penetration into a writing surface on which the ellipsograph is mounted so that the calibrated beam and the horizontal member 18 may be level when supported during operation.

As more clearly shown in Fig. 2, the bracket 25 is provided with a web 40 that has an opening to rotatably support in a fixed position one end of a square shaft 41 in the bearing 42. The other end of the shaft 41 extends through the vertical web of the rearwardly extending angle bracket 43 that is connected to the forwardly extending and upwardly projecting rider 44. The end of shaft 41 is fastened to the section 33 for rotation thereon. A rear plate 46 is retained against the back of the beam with the knurled head screw 47 passing through the slot 28 for threadable engagement with the capped opening (not shown) in the rear plate 46.

The shaft 41 at the bracket 43 has mounted thereon a miter gear 48 that is rotatably received in the vertical web of the bracket 43 for slideable movement along the shaft. A bevel gear 49 is mounted at the end of shaft 41 at the web 40 of the bracket 25 to be in driving engagement with the fixed bevel gear 24 that is supported on the shaft 23.

Suspended below the calibrated beam 13 and depending from the horizontal web of the angle bracket 43 is the drawing instrument supporting carriage 15. A miter gear

50 engaging with the gear 48 has a downwardly projecting shaft 51 that extends through the spacer 52 to which the shaft is securely fastened and the shaft 51 extends through the elongated slot 53 in the horizontal web 54 of the carriage 15. A knurled head screw 55 extends through the web slot 53 and is threadably fastened to the spacer 52 for a purpose to be described hereinafter. Carriage 15 has a vertical web 56 that is graduated on the front face thereof in increments which represent the numerical difference between the length of the major axis and the length of the minor axis. In the embodiment illustrated the scale is represented as one-fourth to one. Therefore, with a major axis of 7 inches and a minor axis of 3 inches a resulting setting on the scale would be placed at the position marked 4. An indicia mark 57 is inscribed on the front of the spacer 52 with the mark being in direct alignment in the plane of the axis of shaft 51.

5 A vertically mounted sleeve 58 is securely fastened to one end of the carriage web 54. The sleeve 58 is tubular and receives therein an insert sleeve 59 which is in threaded engagement therewith. A writing instrument supporting sleeve 60 is telescopically received in the sleeve 59 and has a spring 61 therein and a projecting stud 62 that extends through the elongated slot 63 in the sleeve 59 to permit the writing instrument, such as a lead point 64 to be resiliently supported in a projected position. Suitable knurled nuts 65 and 66 retain the sleeve members constituting the writing instrument in position in a conventional collet grip manner.

25 In one preferred embodiment of the present invention the gears 24 and 49 are bevel gears having a 2 to 1 ratio with the gears 48 and 50 being miter gears having a 1 to 1 ratio. It will be readily apparent that for use with small ellipses, the carriage 15 during rotation will be introduced into the opening 38 that is formed in the ground-engaging leg member 14, thus providing an appreciably increased range for describing small ellipses.

30 In operation, assuming that an ellipse having a major axis of 7 inches and a minor axis of 3 inches is desired, the setting will be as follows: The index mark 57 on the spacer 52 is placed directly in line with the calibrated mark on the carriage scale appearing on the web 56 indicating the difference in length between the major and minor axes by initially loosening the knurled head screw 55 and sliding the carriage 15 through the elongated slot 53 until the index mark 57 is directly over the calibration that is marked 4. Retaining the setting performed on the carriage as above, the knurled head screw 47 is then loosened, and the rider 44 which supports the entire carriage is then shifted so that the zero (0) graduation having the arrowhead 67 thereon points to the lower scale at the position that represents the length of the major axis. The knurled screw 47 is then tightened to lock the assembly in position. In this example, the arrow head 67 on the carriage web 56 will be positioned so that the arrowhead points to the mark 7. The pivot point 40 on the ground-engaging leg 14 will then be placed on the intersection 0 of the major axis X—X and the minor axis Y—Y with the notch 22 on the foot 21 registering with the X—X axis projected. With one hand the grip 19 is supported to stabilize the instrument in a vertical plane. The other hand may then engage the portion 34 on the free end of the beam 13. Upon rotating the beam about the pivot point 40 the fixed gear 24 that engages the gear 49 will cause the gear 49 to rotate the shaft 41 which shaft in turn will rotate the gear 48 that is on the same shaft. Upon rotation of the gear 48, the gear 50 affixed to the spacer 52 will be driven. Since the shaft 51 extends through the slot 53 and the knurled screw 55 passes through the slot 53 to engage the spacer, the carriage 15 will be rotated upon rotation of the gear 50. Clockwise rotation of the calibrated beam will produce counterclockwise rotation

4 of the carriage on which the writing instrument is attached.

5 Where conjugate axes are known as where an ellipse of a given size is to be described in projection at a designated angular disposition, the instrument setting is as follows for an ellipse designated as a 7 inch by 60 degree ellipse: A setting obtained from a chart corresponding with the particular instrument will be employed as indicated below for the instrument illustrated and the setting indicated for 10 a 7 inch major axis at 60 degrees indicates a reading of F¹ on the upper scale 29. To obtain this setting the knurled screw 47 is loosened and the edge 68 on the rider 44 is placed at the F¹ graduation on the upper scale 29. Thereafter the knurled screw is locked in position. Also, the knurled screw 55 is loosened and the carriage 15 is displaced so that the arrowhead 67 points to the major axis on the lower scale 27 at the mark 7 and the knurled screw 55 is then tightened. The operation for making the construction is as above described.

15 The following chart is illustrative of one ellipsograph instrument embodying the inventive concept wherein the chart tabulates various settings for ellipses in projection drawing.

	Major Axis, inches	60°	45°	30°	Major Axis, inches	60°	45°	30°

40 Obviously, many modifications and variations may be made in the construction and arrangement of the frame, the calibrated beam, and the carriage as well as modifications made to the mounting for the components without departing from the real purpose and spirit of this invention. It is, therefore, to be understood that within the scope of the appended claims many modified forms of the present inventive concept as well as the use of equivalents and alternatives may be reasonably included and modifications are contemplated.

45 What is claimed is:

1. An ellipsograph instrument comprising an open stand having a horizontally extending member and a depending ground-engaging leg at one end of the member and a foreshortened leg at the other end of the member, 55 said foreshortened leg having a downwardly extending shaft, a calibrated beam horizontally supported and rotatably mounted intermediate the beam length on said member shaft, said beam having a depending ground-engaging leg having a carriage-receiving opening therein, said leg of the beam having a ground-engaging pivot point coaxially aligned and in spaced relation with said member shaft, a first gear fixedly mounted on said member shaft, a shaft rotatably supported on said beam, a second gear on the beam shaft engaging said first gear and a third gear supported in spaced relation to said second gear on the beam shaft, said first gear driving the second gear and shaft upon rotation of the beam, the third gear being slidable on the beam shaft, a drawing instrument supporting carriage rotatably suspended from said beam intermediate its length and adjustable along said beam, a fourth gear fixed to said carriage and engaging said third gear on said beam for rotating said carriage upon beam shaft rotation, a drawing instrument depending from said carriage, and indicia on said beam and said carriage for setting major and minor axis lengths whereby

upon rotation of said beam the carriage will rotate and the drawing instrument will describe an ellipse.

2. An ellipsograph instrument comprising a stand having a depending ground-engaging leg at one end and a foreshortened leg at the other end, a calibrated beam rotatably mounted intermediate the beam ends on said foreshortened leg, said beam having a depending leg with a carriage-receiving opening therein, said beam leg having a pivot point coaxially aligned and in spaced relation with said foreshortened leg, said beam extending horizontally, a first gear mounted on said foreshortened leg, a shaft rotatably supported on said beam, a gear on the beam shaft in driving contact with the first gear, said beam shaft gear being in driving engagement with said first gear, a beam shaft supporting gear spaced from the other gear on the beam shaft and slidable on said shaft, a carriage rotatably supported from said beam intermediate its length and adjustable along said beam, a carriage revolving gear fixed to said carriage in driven engagement with the beam shaft slidable gear for revolving said carriage, a drawing instrument depending from said carriage, and a scale having indicia on said beam and on said carriage for setting major and minor axis lengths.

3. An ellipsograph instrument comprising a stand having a horizontally extending member and a depending ground-engaging leg at one end of the member and a foreshortened leg at the other end of the member, a calibrated beam swingably mounted on said foreshortened leg, said beam having a depending leg having a return reach to provide a carriage-receiving opening, said leg having a ground-engaging pivot point in line with said foreshortened leg and in spaced relation therewith, said beam extending horizontally beneath said stand member, a shaft rotatably supported on said beam, means on the foreshortened leg to rotate said beam shaft upon rotation of said beam, a gear slidably mounted on the beam shaft in spaced relation to said means, a drawing instrument supporting carriage rotatably supported and adjustably suspended from said beam, a gear mounted on the carriage to engage said slidable gear on said beam supported shaft, a drawing instrument depending from said carriage, and a scale on said carriage and said beam for setting major and minor axis lengths whereby upon rotating said beam the carriage will rotate to describe an ellipse with said drawing instrument.

4. An ellipsograph instrument comprising a stand having a depending ground-engaging leg at one end and a foreshortened leg at the other end, a calibrated beam rotatably mounted on the foreshortened leg, said beam having a depending leg having a carriage-receiving return bend opening therein, said leg having a ground-engaging pivot point in axial alignment and in spaced relation with said foreshortened leg, a shaft rotatably supported on said beam, means on the foreshortened leg to rotate said beam shaft upon rotation of said beam, a drafting instrument supporting carriage rotatably supported and adjustably mounted from said beam, means on said beam shaft for revolving said carriage, a drawing instrument depending from said carriage, and a scale on said beam and on said carriage for setting major and minor axis lengths whereby upon revolving said beam the suspended carriage will rotate on the beam to describe an ellipse.

5. An ellipsograph drawing instrument comprising a beam supporting stand having a ground-engaging leg and a foreshortened beam supporting leg, a calibrated beam rotatably mounted on the beam supporting leg, one end of said beam extending freely and the other end of said beam having a depending return bend downwardly extending leg, the terminal end of said return bend leg having a pivot about which the beam may rotate, said point being in axial alignment with said beam supporting leg, a gear fixed on said beam supporting leg, a beam supported rotatable shaft extending parallel to said beam, said beam supported shaft having mounted thereon in

spaced relation a pair of gears, one of said pair of gears cooperating with said fixed gear on the beam supporting leg and the other gear of said pair of gears being slidably mounted on the beam shaft, a drawing instrument supporting calibrated carriage rotatably suspended and slidably retained on said beam, said carriage having means thereon for cooperating with said gear slidable on the beam supported shaft, a rider slidably mounted on the beam and connected to said carriage, and means on said carriage for locking the carriage in a selected position on the calibrated beam.

6. An ellipsograph drawing instrument comprising a beam supporting stand having a ground-engaging leg and a foreshortened beam supporting leg, a calibrated beam rotatably mounted on the beam supporting leg, one end of said beam extending freely and the other end of said beam having a depending return bend downwardly extending leg, the terminal end of said return bend leg having a point about which the beam may rotate, said point being in axial alignment with said beam supporting leg, a beam supported rotatable shaft extending parallel to said beam and mounted thereon, means on the beam supporting leg for rotating said shaft as said beam is rotated about said beam supporting leg, said beam supported shaft having mounted thereon in spaced relation to said shaft rotating means a gear slidable on said shaft, a drawing instrument supporting calibrated carriage rotatably suspended and slidably retained on said beam, said carriage having a gear connected thereto for cooperating with said gear slidable on the beam supported shaft, a rider slidably mounted on the beam, said rider having means for supporting the carriage thereon, and means for guiding the slidable movement of the carriage and releasably locking the carriage in a predetermined position relative to the calibrated beam.

7. An ellipsograph comprising a stand having a ground-engaging leg, a calibrated beam rotatably supported from the stand, said beam having a free end and a ground-engaging leg at the other end, said leg having a return bend, a shaft rotatably mounted on the beam, means on the stand for rotating said shaft upon rotation of the beam, a calibrated drafting instrument supporting carriage suspended from said beam and adjustable thereon, said calibrated drafting instrument being operable through the return bend in said ground-engaging leg, and means on said shaft for rotating said carriage upon revolving said beam.

8. An ellipsograph comprising a stand having a ground-engaging leg and a beam supporting leg, a calibrated beam rotatably mounted on the beam supporting leg, said beam having a depending ground-engaging leg at one end, said depending leg having a return bend therein, a shaft rotatably mounted on said beam, means on the beam supporting leg for rotating said shaft, a calibrated carriage adjustably and rotatably suspended from said beam for operation in close proximity to the depending leg for passage of the carriage through the return bend therein, means on said shaft for rotating said carriage upon rotation of said beam on the beam supporting leg, and a writing instrument supported on the carriage for describing an ellipse upon rotation of said beam and supported carriage.
